UNITED STATES PATENT OFFICE.

ALBERT C. ALTHOUSE, OF DUBLIN, PENNSYLVANIA.

BROOM-BRIDLE.

1,111,553.

Specification of Letters Patent. Patented Sept. 22, 1914.

Application filed June 30, 1913. Serial No. 776,687.

To all whom it may concern:

Be it known that I, ALBERT C. ALTHOUSE, a citizen of the United States, residing at Dublin, in the county of Bucks and State of Pennsylvania, have invented a new and useful Broom-Bridle, of which the following is a specification.

This invention relates to broom attachments and more particularly to a broom bridle which may be secured around the broom bristles in what is termed a non-resilient manner when the broom is to be used for scrubbing and to further provide means whereby the said attachment may be resiliently secured to the bristles to allow for the flexing thereof when the broom is to be used for sweeping and similar purposes.

A further object is to provide a broom attachment formed of two similar bands connected by resilient springs interposed therebetween and to form inwardly projecting spurs from the said bands which are adapted to engage the broom bristles and hold the attachment securely thereto.

25 A further object is to provide the said bands with a plurality of apertures at their end portions whereby a suitable range of adjustment is had, and to secure to the said bands suitable rods which are positioned within the said coiled springs and hold the bands in a non-resilient manner so that considerable strength will be imparted to the broom bristles when the broom is to be used for scrubbing and allied purposes.

35 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

45 In the drawings accompanying this specification, and forming a part thereof, the preferable form of my invention is illustrated, in which:

Figure 1 is a view in perspective with my improved broom attachment secured thereto. Fig. 2 is a side view illustrating the connection between the two bands. Fig. 3 is a top plan view of the attachment with the holding rod out of engagement so that the bands will be resiliently secured together which allows for the flexing and play

of the broom bristles. Fig. 4 is a fragmental transverse view of one of the bands and holding studs.

Referring to the drawings in which similar reference numerals designate corresponding parts throughout the several views, 5 is a broom and includes the bristles 6 and typifies the ordinary broom construction.

The attachment which is to be secured 60 adjacent the lower extremities of the broom bristles includes the two bands A and B perfectly similar so that a description of one applies with equal relevancy to the other. The band A is formed with the body portion 8 which is provided with a plurality of adjusting apertures 9. The body portion 8 lies against or contacts with the flatter portions of the bristles as shown in Fig. 1 and connected thereto is the hooked 65 end 10. The latter conforms generally to the contour of the edge of the broom bristles around which it extends. The extremity of the hooked end 10 is provided with the two transversely alined apertures 11-12 70 therein, which provide suitable securing means for the holding of the coiled spring 13 and the straight rod 14, it being noted that the rod 14 is formed integral with and an extension of the coiled spring 13. The 75 stress however upon the spring 13 or rod 14 does not transmit itself to the other but to the hooked end of the band.

In order to prevent the attachment from riding up upon the bristles or from passing 80 downwardly therefrom, the bands are provided with a number of inwardly struck spurs 15 represented in the present drawings as being substantially triangular in outline to thereby wedgedly engage the bristles as well as frictionally grip the same. 85 As will be evident from a reference to Fig. 3, the spurs extend throughout the hooked portion of the band so that a plurality of the same is provided which renders unnecessary any attachment passing over the shoulders of the broom head.

100 Permanently secured to the apertures 11 and 12 of the hooked portions of the bands are the coiled or tension springs 13 and the straight tie rods 14. The remote ends of the springs and tie rods are bent upon themselves and detachably engage the apertures 9 of the body portion of the bands. Thus 105 it will be apparent that there are two similar bands and two similar springs and tie rods extending therebetween.

In the practical use of my improved attachment, the bands A and B are installed upon the broom bristles and the free ends of the coiled springs and tie rods are then brought into engagement with the proper apertures of the opposite bands. When it is desired that the bristles shall remain substantially rigid and prevent the flexing thereof, the tie rods 14 are secured in position, it being noted that with the tie rods in position it is of little or no moment whether the resilient springs 13 are secured to the bands or not. With the tie rods properly adjusted in the respective openings of the bands the width of the bands imparts considerable strength to the broom bristles and holds the same together in a rigid mass. When, however, it is desired that a certain amount of play or resiliency be embodied in the broom bristles, one end of the tie rods are disengaged from the apertures 9 and the springs are then the only means holding the two bands together, and due to the resiliency thereof will allow the bands to move longitudinally and allows the bristles to flex or bend. The spring coils 13 house the tie rods 14 therein and prevent the latter from swinging about and being in the way when they are disengaged from the apertures 9.

Having thus fully described the invention what I claim to be new and original with me is:

1. A broom attachment comprising two similar bands, each of said bands being provided with a plurality of inwardly projecting spurs adapted to engage broom bristles, and further provided with a plurality of longitudinally arranged apertures adjacent one end, the remote end of said band bent upon itself and provided with an aperture therein, and a holding and adjusting member extending between dissimilar ends

of the bands, said holding and adjusting member including a wire extending through the last mentioned aperture of the band, one arm of the wire member coiled upon itself and forming a spring with the remote end thereof hook shaped and adapted to adjustably engage the longitudinally arranged aperture of the adjacent dissimilar end of the adjacent band, the other arm of the said holding member forming a rod with the remote end thereof bent, adapted to engage and rigidly hold the adjacent band end. 55

2. A broom bridle including similar bands, said bands each including a body portion with a bent end, the said body portion adapted to contact with the side walls of the broom bristles and with the bent ends thereof adapted to embrace the edge walls of the bristles, said bands provided with a plurality of inwardly struck spurs adapted to frictionally grip and wedgedly engage the said bristles, each band provided at one end with a plurality of adjusting apertures and with an aperture at its remote end, a tie rod and a coiled spring permanently secured to the last mentioned aperture and detachably and adjustably engaging one of the first mentioned apertures, said tie rod positioned in and housed by said coiled spring, said tie rod adapted to hold the bands in non-resilient engagement with the broom bristles, said tie rod detachable from the first mentioned aperture for the resiliency holding of the bands by the said coiled springs. 75

In testimony that I claim the foregoing as my own, I have hereto affixed my signature in the presence of two witnesses. 80

ALEX C. ALTHOUSE.
